(57) **CLAIM**

The ornamental design for a hand-held cable cutter, as shown and described.

DESCRIPTION

FIG. 1 is a top, rear, left side perspective view of a hand-held cable cutter showing our new design;

FIG. 2 is a front elevation view thereof;

FIG. 3 is a rear elevation view thereof;

FIG. 4 is a right side elevation view thereof, the left side being a mirror image.

FIG. 5 is a top plan view thereof; and,

FIG. 6 is a bottom plan view thereof.
